MAKE-UP CAPE

Farol M. Stier, Caro, Mich.

Application March 23, 1954, Serial No. 29,655

Term of patent 14 years

(Cl. D3—3)

Fig. 1

Fig. 3

To all whom it may concern:

Be it known that I, Farol M. Stier, of Caro, county of Tuscola, and State of Michigan, have invented a new, original, and ornamental Design for a Make-up Cape, of which the following is a specification, reference being had to the accompanying drawings, forming a part hereof.

In the drawings:

Fig. 1 is a front elevational view of the make-up cape.
 Fig. 2 is a side elevational view thereof.
 Fig. 3 is a top plan view.

I claim:

The ornamental design for a make-up cape, as shown.
